US00D620924S

(12) **United States Design Patent**
Masui et al.

(10) **Patent No.:** US D620,924 S
(45) **Date of Patent:** ** Aug. 3, 2010

(54) **COMBINED DISC PLAYER, AMPLIFIER, TUNER AND AUDIO PLAYER**

7,372,119 B2 * 5/2008 Nakamura et al. 257/427

FIG. 1 is a top plan view of a combined disc player, amplifier, tuner and audio player showing our new design; and,

FIG. 2 is an enlarged perspective view thereof.

The dot-dash broken lines, which define the bounds of the claimed design, form no part thereof. The even broken lines environmental are for illustrative purpose and form no part of the claimed design.
